MACHINE FOR STEEPING PELTS

Filed March 8, 1930

UNITED STATES PATENT OFFICE

MAX BLOCH, OF FRANKFORT-ON-THE-MAIN, GERMANY

MACHINE FOR STEEPING PELTS

Application filed March 8, 1930, Serial No. 434,430, and in Germany March 22, 1929.

Machines are already known in which a brush dipping into the steeping liquor applies the steep to the pelt. As however only a small quantity of steep adheres to the brush, the quantity of liquor which the brush applies to the pelt cannot be controlled and is not sufficient for properly carrying out the steeping process. The consequence is that the pelt must be passed several times through the machine, which causes a great loss of time. This disadvantage is even noticeable when steeping by hand, for in this case the steep must be rubbed in once with the hair and once against the hair.

The present invention relates to a steeping machine, in which the steep is applied directly to the pelt by means of an endless band consisting of a porous elastic substance, for instance, spongy rubber, which travels over a roller, dips into the steeping liquor and coacts with a counter-pressure roller and is brushed into the pelt by a brush which coacts with a second endless band surrounding it. By this means the liquor is not only conveyed in sufficient quantity during a single operation and applied to the belt, but is at the same time pressed as deeply into the hair and rubbed in as is required by the felting process to which the hair is subsequently subjected. The new machine also ensures the pelt being conveyed in an absolutely reliable manner and prevents the liquor being splashed.

The new machine provides a further important advantage. The failure of all the machines hitherto placed on the market has resulted in the steeping of pelts being everywhere carried out by hand, in which case it is impossible to avoid the operative coming in contact with the mercury-containing liquor, so that it is impossible to prevent the health of the operative being detrimentally affected. The new machine obviates this disadvantage as well by saving the operative from carrying out a process which is injurious to his health and, therefore, satisfies a long felt hygienic requirement.

In the accompanying drawing a constructional example of the drawing is shown:

Figure 1 being a front elevation of the new machine, and

Figure 2 the cross section through the middle of the same.

To the standards 5 and 6 which are connected together by the stay-bolts 1, 2, 3, 4, housings 7 and 8 are fixed. Between these 55 housings are mounted the two rubber steeping rollers 9, 10. The upper roller rests in two bearings 11 which are guided in the housings 7 and 8 and rest against the springs 13 in the bearing plates 12. The stressing of 60 the springs can be regulated as required by the screws 14. The rubber steeping roller 10 also rests in two bearings 15 and over it travels the belt 16 made of spongy rubber or 65 some similar porous elastic substance. The belt dips into the liquor which is contained in the tank 17. In order that the belt should always be in a slightly tensioned condition, a roller or pipe 18 is placed at the lower end 70 of the same. Below the steeping roller 10 are the squeegee rollers 19 and 20. The rear roller 19 rests in the bearings 21 and the forward roller in the bearings 22 which can be adjusted by means of the hand wheel 23 and the screw spindle 24 in the horizontal direction, so that the roller 20 can be approached to a greater or less extent to the roller 19. This approaching of the roller has the object 75 of partly pressing the liquor with which the spongy rubber belt is saturated, out of the belt again according to whether the pelt to be steeped has to be supplied with a greater or less quantity of steep.

Behind the steeping rollers 9 and 10 are 85 two further rubber rollers 25 and 26, these rollers rest in the bearings 27 and 28. The upper bearings are yielding and rest against the springs 29 housed in the bearing plate 12. The stressing of these springs can be regulated according to requirement by the screws 90 30.

Over the roller 25 travels the endless band 31 made of rubber cloth or the like. This band travels over the rubber roller 33 which 95 is journaled in the bearings 32 and can be tensioned by the rollers 34 and 35. The latter rollers rest in the eyes of two tensioning screws 36 and 37. The speed of the forward feed of the belt 31 is the same as the peripheral speed of the steeping roller. 100

With the belt 31 there coacts the considerably more rapidly running brush roller 38 which rests at both ends in bearings 39 and is driven by means of a driving belt and the 5 two belt pulleys 40 and 41 from the main shaft 42. The latter is driven from the belt pulley 66.

From the shaft 42 which is rotated by the belt pulley 66 the steeping roller and the belt 10 31 are also driven. On the other end of the main shaft 42 is mounted the chain wheel 43 which coacts through the chain 44 with the chain wheel 45. The latter is mounted on the hub of the chain wheel 46 which runs on the 15 pin 65 fixed in the bearing 64 and acts through the chain 47 on the chain wheel 48 driving the shaft 49. On the other end of the shaft 49 is the toothed wheel 50 which meshes on the one hand with the wheel 51 20 keyed on the shaft of the lower steeping roller and on the other hand with the toothed wheel 52 which drives the rubber roller 28 and coacts with the wheel 53 fixed on the shaft of the roller 25. In this way not only the spongy 25 rubber belt 16 is driven but the belt 31 as well.

On the shaft 49 there is also mounted the chain wheel 54 which through the chain 55 (Figure 2) drives the chain wheel 56 and the rubber roller 57 which is mounted below the 30 brush roller. The roller 57 rests in the bearings 58 fixed on the standards 5 and 6 and serves the purpose of guiding the endless conveyor band 59 which also runs over the roller 60. The latter roller is also journalled in two 35 bearings 61 which are fixed on the main standards and is capable of being adjusted by means of the hand wheels 62 and the screw spindles 63.

To one of the housings 7 or 8 a device is 40 fixed for measuring the quantity of steep worked into the pelts. This measuring device consists of a liquid pressure gauge 67 in combination with a flexible rubber tube 68 and a glass tube 69 which extends into the 45 steeping liquor in the storage tank 17 so that the level of the liquor can be read any time on the scale of the pressure gauge. The pressure gauge scale is so graduated that one 50 scale division corresponds to one litre of the quantity of liquor used, so that the latter can be read off at any time on the scale for a definite number of pelts.

It is of the greatest importance to check 55 accurately the quantity of liquor for the pelts to be steeped, as a definite prescribed quantity of liquor is required according to the kind of pelt in order to ensure a satisfactory further treatment of the hair materials in the manufacture of hats. The provision of 60 the measuring device makes it possible so to regulate the supply of liquor that the correct quantity of steeping liquor shall be applied to the pelts to be steeped.

The machine operates in the following 65 manner:

The pelt to be steeped is introduced between the steeping rollers 9 and 10 with the hair side downwards, the hairs of the pelt consequently come into contact with the spongy rubber belt 16 which applies the steep carried along with it to the hair. If the supply of steeping liquor should be too great, the squeegee roller 20 is pressed with somewhat greater force against the spongy 70 rubber belt 16 whereby a portion of the liquor is pressed out of the latter. After passing the steeping roller the pelt travels between the rollers 25 and 26 and is pushed by them against brush roller 38. The brush roller deflects the pelt upwards and presses it against the belt 31 which runs at the same velocity as the steeping rollers 9 and 10. The pelt thus lies between the belt 31 and the brush roller 38, so that the latter which runs more 80 rapidly than the belt 31 brushes the steeping liquor well into the hairs of the pelt. After the operation is complete the pelt falls on to the endless conveyor band 59 and is conveyed away by it. Through the belt 31 being used any splashing of the steeping liquor while 85 it is being rubbed on is prevented. The persons attending the machine are therefore protected from the injurious effects of the steep.

After a definite number of pelts has passed through the machine, the volume of the quantity of steep used in treating them is read off on the liquid pressure gauge. In this way the quantity can be constantly checked which is of the greatest importance in the further treatment of the hair in the manufacture of hats. Should the operative judge that the consumption of steep is too great, he compresses the spongy rubber belt more 90 strongly by means of the two squeegee rollers 19 and 20 and if the consumption is too small he separates the rollers slightly more. The operative is thus able to regulate the action 95 of the machine as desired.

What I claim is:

1. A machine for steeping pelts including 110 a pair of pelt feeding rollers, a steeping liquid tank below said rollers, a liquid supplying belt extending into said tank and passing over one of said rollers, and brushing means located at the discharge side of said 115 pelt feeding rollers.

2. A machine for steeping pelts including 120 a pair of cooperating pelt feeding rollers, a liquid reservoir arranged below said rollers, a sponge rubber belt extending into said reservoir and passing over the lower one of said pelt feeding rollers, and brushing means arranged at the discharge side of said pelt feeding rollers for brushing the liquid into the hairs of the pelt.

3. A machine for steeping pelts including 125 a pair of pelt feeding rollers, a liquid reservoir arranged below said rollers, an endless liquid supplying belt extending into the reservoir and passing over the lower one of said 130

rollers, a pelt conveyor, brushing means arranged between the pelt feeding rollers and said conveyor, said brushing means being adapted to receive the pelt from the pelt feeding rollers and brushing the liquid into the hair of the pelt while moving it toward said pelt conveyor.

4. A machine for steeping pelts comprising a pair of pelt feeding rollers, a steeping liquid reservoir arranged beneath said rollers, an endless liquid supplying belt extending into the reservoir and passing over the lower one of said pelt feeding rollers, and brushing means arranged at the discharge side of said pelt feeding rollers, said brushing means comprising a rotary brush, pelt guiding rollers arranged between the rotary brush and the pelt feeding rollers, and an endless belt passing over the upper one of said pelt guiding rollers and having the lower reach thereof extending over and about the rotary brush.

5. In a pelt steeping machine, pelt feeding rollers, means for supplying steeping liquid to a pelt passing between said feeding rollers, and means for brushing the liquid supplied to the pelt into the hairs thereof comprising a pair of pelt guiding rollers, a rotary brush arranged at the discharge side of said rollers and an endless belt passing over the upper one of said pelt guiding rollers and having the lower reach thereof extending over and about said rotary brush whereby the liquid carried by the hairs of the pelt may be brushed into the same.

35 6. A machine for carrottting pelts comprising, in combination, a tank for the carrottting liquor, a roller arranged over the tank, an endless belt of porous elastic material running over said roller and dipping into the carrottting liquor in the tank in order to convey and press the liquor into the pelt, a counter-pressure roller arranged over the belt-roller and coacting therewith, a brush at the discharge side of said rollers for distributing the liquor into the pelt, and a second belt of elastic material arranged over the brush and partially embracing the same.

7. In a machine for carrottting pelts, rollers adapted to receive the pelt with the hair side downward, means in the form of an endless porous belt for supplying carrottting liquor to the hair side of the pelt in regulated quantity, and means for brushing the liquid supplied to the hairs of the pelt comprising a rotary brush and a flexible covering therefor, the rotary brush and the cover rotating at different speeds whereby the brush works the liquid into the hair as the pelt is pressed against the flexible cover and the pelt is simultaneously moved to be discharged from the machine.

In testimony whereof I have affixed my signature.

MAX BLOCH.
